(57) **CLAIM**

The ornamental design for a notebook computer as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate portions of the notebook computer that form no part of the claimed design. The oblique line shading shown in the drawings indicates a transparent or translucent surface.

1 Claim, 8 Drawing Sheets
